Inventor

By his Attorney, *Alfred Kapp*

UNITED STATES PATENT OFFICE.

BYRON B. GOLDSMITH, OF NEW YORK, N. Y.

INK CAPSULE.

Application filed March 2, 1922. Serial No. 540,488.

To all whom it may concern:

Be it known that I, BYRON B. GOLDSMITH, a citizen of the United States, residing in New York, county and State of New York, 5 have invented a certain Improvement in Ink Capsules, of which the following is a specification.

The many inconveniences and disadvantages of transporting and storing ink in liquid form are well recognized and various ways have been proposed for avoiding them by supplying apparatus whereby solid ink-producing material might be supplied to the consumer in such a way as to make it 10 possible to produce a liquid ink by the mere addition of water when and where the ink was needed.

Dry ink powders variously compounded, and intended to be used by solution in water 15 at or near the time and place of use, are well known in the art; but they are awkward to use and uncertain in effect, particularly in the hands of the average unskilled consumer.

The present invention relates to a novel 20 means for the preparation of ink powder of any kind in a manner insuring the making of ink of exactly such proportions as are deemed best in a given case, without waste of powder and practically instantaneously. 25 At the same time my improvement provides a very convenient package for shipping ink powder ready for instant use, which package perfectly protects the powder and keeps it in condition for insuring perfect results 30 when used. The invention also has the advantage that it prevents accidental spilling on hands, clothing and so forth.

The principal or basic elements of the invention, which is claimed as novel per se, is 35 a capsule, which may be given a variety of shapes, but is always characterized by the presence of a thin layer of ink powder (preferably uniformly distributed) which is confined between two protective layers of 40 a permeable nature, although not necessarily in contact with both layers. The protective layers or either of them should be made of a permeable material such as cloth or the like.

These capsules may be combined with a 45 supporting guiding element to form cartridges or with appropriate vessels used as ink stands, and both of these combinations form the subject matter of certain of the claims herein.

50 Certain embodiments of this invention are

illustrated by way of example in the accompanying drawings wherein Figures 1 and 1^a are views partly in section and partly in perspective showing two forms of a circular capsule, Figure 2 is a sectional view of a simple form of cartridge with a removable capsule, Figure 3 is a sectional view of another form of cartridge provided with a number of capsules, Figure 4 shows a combined capsule and cartridge in section, Figure 5 is a partial sectional view of a modification of the device shown in Figure 4, Figure 6 is a sectional view of an inkstand in which the device of Figure 4 is an element, Figure 7 is a view partly in elevation and partly in section showing another mode of applying the invention to an inkstand and Figure 8 is a view in section of a drum-shaped capsule.

In the simplest form of capsule a thin layer of ink powder 10 is spread uniformly over a sheet or layer 11 or permeable material, preferably cloth or the like, and over this is placed a second similar layer 12, the whole being fastened together at the perimeter, as at 13.

As shown in Figure 1^a, there may be a central permeable layer 14, having thin layers of ink powder 15 and 16 on its opposite faces, confined in place by outer permeable layers 17 and 18.

In use, water is simply poured through a capsule of this kind and ink is produced. No shaking or stirring is required and none of the powder can get loose to stain the fingers, clothing, etc.

In Figure 2 is shown a simple form of cartridge for putting to use the simple capsule of Figure 1 or 1^a. This comprises a support and pouring tube 19, to one end of 95 which the capsules can be applied so as to entirely close the opening, as shown at 20. The capsule may be applied to the tube 19 in any manner, as, for instance, by means of the threaded collar 21.

Where a larger quantity of ink or a more intense ink is to be made at once, a number of capsules 22 can be inserted at intervals in the main tube 19, being held apart in parallel relation by short interior friction 105 sleeves 23, or otherwise.

Figure 4 shows a capsule and cartridge in one, the whole having a cylindrical form. Here an internal support of perforated material 24 may be used around which are suc- 110

cessively wound the inner permeable layer 25 and the outer layer 26, separated by the uniform layer 27 of ink powder.

As shown in Figure 5^a, a cylindrical capsule of this character may be made by first forming a flat capsule like that in Figure 1, but much larger, and rectangular in form, and then uniting the edges of the sheet to form the cylinder 28, by cementing or 10 sewing.

This form of capsule can be conveniently used as a component part of an inkstand, as shown in Figure 6. Here the capsule, as 28, closed at one end as at 28^a, is simply set on 15 its closed end in a vessel 29, and water is poured into the latter outside of the capsule. This water percolates through the capsule forming ink within it, and the interior of the capsule is used as a dipping space for 20 the pen.

In Figure 7, the ink stand 30 has a threaded filling orifice at 31 over which the capsule 20 is laid, being held in place by the removable funnel 32, screwed on over the 25 orifice 31. Water poured into the funnel will percolate through the capsule into the ink-stand and be converted into ink on the way.

As shown in Figure 8, the permeable 30 sides of the capsule need not necessarily both be in contact with the powder. Here the sides 33 and 34 are held apart by a rim 35, so as to form a small drum-shaped capsule, partly empty and partly filled with the 35 powder 36.

Although I have used the term ink powder, I desire to be understood as also covering thereby particles of a larger size than actual powder as in some cases there is 40 an advantage in using such larger sizes with percolating spaces between them.

The examples described above are sufficient

to make it clear that many changes may be made in the form and arrangement of the devices described without departing from 45 the scope of the invention which is not limited to the details herein described and shown.

What is claimed—

1. An ink capsule consisting of a hollow 50 disc, the opposite faces of which are made of material permeable to liquid, and comminuted ink-producing material between the faces.

2. An ink capsule comprising two or more 55 retaining layers of material permeable to liquid but adapted to retain powder and sealed around their edges, and one or more layers of ink powder between said retaining layers. 60

3. An ink capsule comprising two substantially parallel layers of cloth sealed together around their edges and enclosing a layer of comminuted ink-producing material. 65

4. An ink cap comprising two or more 65 layers of material permeable to liquid sealed at their edges and enclosing a layer of ink powder shallow enough to permit ready passage of water.

5. An ink cartridge comprising a tube having closing means at one end, said tube being formed of two or more retaining layers of material permeable to liquid but adapted to retain powder, and one or more layers of ink powder between said retaining layers. 70

6. An ink capsule as in claim 2 wherein the united layers are bent around as a whole with edges brought together to form a cylinder; in combination with a reinforcing perforated cylinder. 80

In testimony whereof I have hereto set my hand on this 20th day of February, 1922.

BYRON B. GOLDSMITH.
